PRINTING STATION FOR AUTOMATIC DATA PROCESSING

Charles A. Pycha and Frank Wilkey, Jr., Rochester,
Minn., assignors to International Business Machines
Corporation, Armonk, N.Y.

Filed Apr. 18, 1973, Ser. No. 352,132

Term of patent 14 years

Int. Cl. D14—02

U.S. Cl. D26—5 C

FIG. 1

FIG. 2

FIG. 1 is a front perspective view of a printing station for automatic data processing, showing our new design;

FIG. 2 is a rear perspective view thereof.

We claim as our invention:

The ornamental design for a printing station for automatic data processing, as shown.
